UNITED STATES PATENT OFFICE.

ELBRIDGE R. HOLMES, OF WORCESTER, MASSACHUSETTS, AND MARTIN R. ABRIAL, OF DANBURY, CONNECTICUT, ASSIGNORS TO CROMPTON & KNOWLES LOOM WORKS, OF WORCESTER, MASSACHUSETTS, A CORPORATION OF MASSACHUSETTS.

LET-OFF FOR LOOMS.

Application filed July 22, 1927. Serial No. 207,783.

This invention relates to improvements in let-off devices more particularly adapted for narrow ware looms and it is the general object of the invention to provide convenient means for facilitating replacement of exhausted warp beams.

In looms for weaving such fabrics as ribbon etc. it is not uncommon to arrange the warp threads for each fabric on a plurality of beams which are mounted on a support such as that set forth in prior patent to Holmes and Hutchins No. 1,517,150. As shown in that patent several beams together with their friction let-off devices are carried by an upright bar the upper end of which is pivoted to the beam and the lower end of which is detachably held in fixed position. The form of support shown in said patent is found satisfactory for the lower beams which are farthest from the pivot of the bar, but replacement of the upper beams makes it necessary to swing the bar considerably before said upper beams will clear neighboring beams due to the closeness of said beams to the pivot of the bar. It is an important object of our present invention to provide a sliding support for the upper end of the bar on which the beams are mounted, the purpose of this construction being to permit the upper beams to be moved rearwardly a sufficient distance to clear the adjacent beams.

In certain looms we find that the upper beams are at a considerable height and are not within easy reach of all mill operatives and it is a further object of our invention to provide means whereby the whole set of warp beams will not only be moved rearwardly to clear adjacent beams but will also be lowered so as to be more accessible.

With these and other objects in view which will appear as the description proceeds, our invention resides in the combination and arrangement of parts hereinafter described and set forth in the claims.

In the accompanying drawings, wherein we have shown a convenient embodiment of our invention,

Fig. 1 is a vertical section through a portion of the top rigging of a narrow ware loom showing our invention applied thereto,

Fig. 2 is an enlarged rear elevation taken in the direction of arrow 2, Fig. 1 and showing the manner of securing the lower end of

one of the supports for the spools in fixed position.

Fig. 3 is an end elevation taken in the direction of arrow 3, Fig. 2 parts being in section,

Fig. 4 is an enlarged rear elevation taken in the direction of arrow 4, Fig. 1 and showing the manner of supporting the upper end of one of the beam bars,

Fig. 5 is an end elevation looking in the direction of arrow 5, Fig. 4 and showing the parts in normal position in full lines and in warp spool changing position in dotted lines, and

Fig. 6 is a rear elevation on a reduced scale of the loom taken in the direction of arrow 4, Fig. 1.

Referring to the drawings we have shown a loom side 10 having a warp frame 11 mounted vertically thereon. Said frame 11 supports a plurality of guides 12 over which the warp threads W extend. The warp threads are supplied by a plurality of warp beams 13 which may be supported and also tensioned by devices T substantially as set forth in the aforesaid patent. Said warp beams are arranged in vertical groups, as shown in Fig. 6 and it is to be understood that there will be as many vertical groups or sets of warp threads as there are woven webs in the loom. Each set of warp beams is rotatably mounted on a carrier bar 14 extending vertically at the rear of warp frame 11 and our present invention relates particularly to the method of supporting these bars with respect to the frame 11.

As shown more particularly in Figs. 1, 2 and 3 the lower end of the warp frame 11 is provided with a cross girt 15 formed substantially U shaped in cross section and affording means by which the lower end of the several carrier bars 14 are supported. For each bar there is provided a bracket 16 having an upright ear 17 through which projects a bolt 18 passing through the lower end of the corresponding bar 14. A winged nut 19 affords ready means for disconnecting the lower end of the bar and the ear. In order to hold said bracket in place we provide as shown herein a pair of hooked bolts 20 to engage the upper part of the girt 15 and a single hooked bolt 21 to engage the lower portion of girt 15. By means of nuts 22 on said hooked bolts the position of

the bracket 16 may be changed longitudinally along the girt 15.

A second cross girt 23 at the upper end of the warp frame 11 provides means for supporting the upper ends of the bars 14. As shown more particularly in Figs. 1, 4 and 5 there is provided a holding plate 24 for each bar 14, said holding plate receiving the ends of a U-bolt 25 which extends around the cross girt 23 and is held in fixed position with respect thereto by means of nuts 26. By loosening said nuts the plate 24 may be moved along the cross girt 23 to correspond with the position of the lower bracket 16 associated therewith.

Secured to each holding plate is a downwardly and rearwardly extending rod 27 having a collar 28 held to the lower end thereof. In order to connect the bar 14 to its guide rod 27 we provide a sliding collar 29 pivotally connected as at 30 to the bar. The collar is free to move along the inclined guide rod 27 and will be arrested in its downward and rearward movement by the fixed collar 28.

As previously stated there are several parallel vertical bars 14 as shown in Fig. 6 with their warp beams and it is frequently necessary to replenish a beam of one group while the other groups are in their normal position. This result can be accomplished by the structure set forth herein in such a way as to enable the attendant to replace the uppermost warp beam conveniently and easily without interference by neighboring warp beams. When making a change the winged nut 19 will be loosened and the lower end of the bar to be moved will be slid off the ear 17, at which time the collar 29 will be free to slide down from the full line to the dotted line position shown in Fig. 5, collar 28 limiting downward movement. The beams and corresponding upright bar 14 will then be in the position shown in dotted lines in Fig. 1 where they will be out of alignment with adjacent beams and bars. After the depleted beam has been replaced the attendant will push upwardly on the lower end of the bar 14 to cause the collar 29 to slide upwardly along the guide rod 27 and when in proper vertical position the lower end of the bar will be slipped over ear 17 and the bolt 18 tightened by means of the winged nut to hold the bar in fixed position.

It is found that by inclining the rod 27 gravity will aid in moving the warp beam to replenishing position and furthermore the warp beams are at a lower level than that ordinarily occupied, thus making the change of beams easier for the attendant. The tension devices indicated generally at T are carried by the bars 14 and cooperate with the beams to hold the warp threads under proper tension. This feature of the device

forms no part of the present invention and is therefore not described particularly but may be made as set forth clearly in the aforesaid patent.

From the foregoing it will be seen that we have provided a very simple means for supporting a set of warp beams and for moving them out of alignment with neighboring beams when a change in the warp is to be made. Furthermore, it will be seen that the movement of the supporting or carrier bar gives practically the same motion to all of the warp beams so that those at the top of the bar will be out of line with adjacent beams to facilitate removal thereof, this advantage not being present in the aforesaid patent. Also, by having the guide rod 27 inclined gravity aids in the placing of the bar and warp beam supported thereby and also lowers the beams so as to facilitate changing thereof by an attendant. Furthermore, the detachable and adjustable connections between the cross girts of the warp frame and the upright carrier bars 14 make it possible to move the set of warp beams to any desired position with respect to the width of the loom.

Having thus described our invention it will be apparent that changes and modifications may be made therein by those skilled in the art without departing from the spirit and scope of the invention and we do not wish to be limited to the details herein disclosed, but what we claim is:

1. In a narrow ware loom, a set of warp beams arranged in vertical alignment, a carrier for said warp beams, located at one side only of the beam, a supporting frame, an inclined guide at the upper end of the carrier, and detachable means to hold said carrier in normal position, said carrier when detached from normal position moving downwardly and rearwardly along the inclined guide, the beams being removable from the carrier in a direction parallel to their axes.

2. In a narrow ware loom, a set of warp beams, a carrier for said warp beams, located at one side only of the beam, a downwardly and rearwardly extending guide, and means defining a connection between the carrier and guide, whereby the carrier is moved downwardly and rearwardly, the beams being removable from the carrier in a direction parallel to their axes.

3. In a narrow ware loom, a set of warp beams arranged in vertical alignment, a carrier for said beams, located at one side only of the beam, a downwardly and rearwardly inclined guide, and connections between the carrier and the guide whereby the guide directs the carrier and beams to have a downward and rearward movement, the beams being removable from the carrier in a direction parallel to their axes.

4. In a loom, a set of vertically aligned warp beams, a support therefor, a downwardly and rearwardly extending guide, and a member slidably mounted on the guide and pivotally connected to the support, said guide directing the member and support to have a downward and rearward movement and said support having an angular movement with respect to the member and also 55 the support.
5. In a loom, a set of vertically aligned warp beams, a support therefor, a warp frame with a downwardly and rearwardly extending rod secured in the upper portion 60 of the frame, a member slidably mounted to move along the guide rod and having pivotal connection with the upper end of the support, and detachable means for attaching the lower end of the support to the warp frame, said guide rod and member acting to 65 guide the warp beams downwardly and rearwardly.
6. In a loom, a set of warp beams, a movable carrier to support the beams, said beams being located on one side of the carrier and removable from the latter in a direction perpendicular from the plane in which the carrier moves, and means to guide the carrier downwardly with respect to the loom.
7. In a loom, a set of warp beams arranged in vertical alignment, a single movable carrier to support the beams, said beams being all disposed on the same side of the carrier and deriving their chief support from the carrier, the beams being removable from the carrier by a motion at right angles to the plane in which the carrier moves, and means to guide the carrier downwardly and rearwardly with respect to the loom.
8. In a narrow ware loom, a plurality of aligned groups of warp beams, a carrier for each group of beams, and means to guide each carrier to a position substantially parallel to but out of alignment with the other groups.
9. In a narrow ware loom, a plurality of aligned groups of warp beams, and means to guide a group to a position parallel to and out of alignment with the other groups.
10. In a narrow ware loom, a plurality of aligned groups of warp beams, and means to guide a group to a position parallel to and out of alignment with the other groups, said means including a downwardly inclined element.
11. In a narrow ware loom, a plurality of groups of aligned warp beams, and means to guide any selected group to a position below and out of alignment with the other groups.
12. In a narrow ware loom, a plurality of groups of aligned warp beams, and means to guide any selected group to a position below and behind the other groups.
13. In a narrow ware loom, a plurality of groups of aligned warp beams, a downwardly inclined guide for each carrier, and a sliding connection between each group and the corresponding guide therefor, whereby each group may be moved downwardly to a 70 position out of alignment with the other groups.
14. In a narrow ware loom, a plurality of groups of aligned warp beams, a carrier for each group, a guide for each carrier extending in a direction transverse of the plane of the groups, and a sliding connection between each carrier and its guide.
15. In a narrow ware loom, a plurality of groups of aligned warp beams, a carrier for each group, a guide for each carrier extending rearwardly, and means defining a sliding connection between each carrier and its guide.
16. In a narrow ware loom, a plurality of groups of aligned warp beams, a carrier for each group, an inclined guide for each carrier extending rearwardly and downwardly, and means defining a sliding connection between each carrier and its guide.
17. In a narrow ware loom, a plurality of groups of aligned warp beams, an inclined guide for each group extending transversely of the plane of the groups, a connection between each group and the corresponding guide, and a stop on each guide to limit movement of the corresponding group.

In testimony whereof we have hereunto affixed our signatures.
